RELASTING MACHINE

Charles E. Johnson, Belmont, Mass., assignor to
 United Shoe Machinery Corporation, Flemington, N. J., a corporation of New Jersey

Application October 11, 1947, Serial No. 779,329

10 Claims. (Cl. 12—15)

1

This invention relates to machines for effecting relative movement between shoes and their lasts, and is herein illustrated as embodied in a machine for mounting shoes on lasts. While the invention is of particular importance in performing this latter operation, commonly known as "relasting," it will be understood that it is not limited to such use or to embodiment in a machine of the particular type herein disclosed.

In making shoes of several different types there is a stage in their manufacture at which the partly finished shoes must be mounted on, and fully distended by, lasts. Making of the so-called "slip-lasted shoe," for example, requires the insertion of a last into a preformed bag-like shoe upper unit. This shoe unit generally comprises a sock lining which has been stitched to an upper and a platform cover or wrapper that has been stitched to the edge of both the upper and the sock lining, the parts thus being secured together before the shoe upper unit is initially mounted on a last. Since the last in its extended condition is relied upon to give such shoes their final form, the last inserting operation becomes a matter of considerable consequence. The shoe unit should be mounted on the last without placing any undue strain on the seam joining the parts of the unit and moreover the seam should be accurately aligned with the edge of the bottom face of the last without any distortion of the parts of the shoe upper unit.

Unless otherwise stated, it will be understood that the term "shoe unit" as used herein means a shoe or other outer footwear in either completed or partially completed condition.

Shoes mounted on lasts by frictional contact with a device such as a rotating concentric roll may not always have their shank portions closely hugging the shank portions of the lasts so as to allow the back parts of the shoes to be mounted over the heel ends of the lasts without the aid of additional operating mechanism. To obtain the best results in seating a last in a shoe upper, especially when the shoe has a deep shank, it will be appreciated that the bottom of the shoe upper should first be tautly drawn over the fore-part of the last to eliminate any wrinkles or looseness of fit and then wiped lengthwise of the last over the shank portion of the last. This tensioning of the shank of the shoe upper unit as it is snugly pressed against the shank portion of the last will then ordinarily permit the rear portion of the shoe to be urged over the back of

2

the last by hand, or if desired, by manipulation of a shoe horn.

An object of this invention is to provide a simple and improved machine by the use of which a shoe unit may be mounted on a last in an expeditious and effective manner with little effort on the part of the operator and without injury to the shoe unit or the last.

For the attainment of the object in view a feature of the invention resides in the provision, in a relasting machine, of a tool in the form of a driven roll mounted eccentrically for frictionally engaging the bottom of a shoe unit partially inserted over a last to draw the shoe unit rearwardly thereon. As illustrated, the impositively engaging eccentric roll is rotated to draw the shoe unit onto the last wherever it contacts the shoe bottom and, more particularly, the eccentricity of the roll serves to shift the locality of its engagement with the shoe bottom from the fore-part, over the ball, and well into the shank.

Further to facilitate relasting operations, the invention provides a depressible jack which is yieldingly mounted and is treadle operated to enable the operator to change the rate of relative movement between the eccentric roll and the bottom of the shoe unit as well as to extend the range of engagement of the roll along the shoe unit bottom. Such means of extending this range of engagement is deemed preferable in most instances to the alternatives of utilizing a larger roll or arranging for heightwise movement of its eccentric axis relatively to the shoe bottom.

The above and other features, including details of construction and novel combinations of parts, will be apparent from the following description of one embodiment of the invention illustrated in the accompanying drawings, in which:

40 Fig. 1 is a view in side elevation of a relasting machine embodying the present invention, the frame being partly broken away and the eccentric roll being shown in the approximate position it occupies at the beginning of the relasting operation;

45 Fig. 2 is a view in end elevation of a portion of the machine shown in Fig. 1, showing the jack carriage mounting and the means for driving the eccentric roll, the latter being partly broken away.

50 Figs. 3, 4 and 5 illustrate diagrammatically certain subsequent and successive positions of the roll in relasting engagement with the bottom of the same shoe unit, the roll being partly in section in Fig. 3 to indicate its construction;

Fig. 6 is a detail sectional view taken along the line VI—VI of Fig. 1 showing the last-locking cam abutting the inner face of a last cone; and

Fig. 7 is a detail sectional view taken along the line VII—VII of Fig. 2 showing the mounting of the rest.

In the drawings, L designates a last and S designates a shoe unit which is being mounted thereon. The tool for mounting the shoe on the last is a friction roll 10 (Fig. 3) comprising an outer annular portion 12 preferably composed of yieldable rubber or a yieldable rubber composition which is bonded to a metal hub 14. Referring to Fig. 1, the hub 14 is eccentrically mounted on and removably secured to a horizontal driven shaft 16 supported in sleeve bushings 18 which are clamped in alined semi-split bearings 20 formed at the upper ends of spaced arms extending upwardly from the frame 22 of the relasting machine. The construction permits an operator readily to dismount the roll when a portion of its working surface has become worn so that it may be reversed end for end and remounted on the shaft to provide an unworn working surface. Rotation of the shaft 16 and the eccentric roll 10 is effected by means of a motor (not shown) driving a multiple V-type pulley 24 (Fig. 2) in a counterclockwise direction as shown in Fig. 1.

The upper portion of the frame 22 constitutes a table having horizontal guideway recesses 25 along which a jack carriage 26 (Fig. 2) is slideable toward and away from the roll 10. A gib 28 may be inserted in a guideway to contact one side of the carriage 26. The gib 28 is adjustable laterally by turning a setscrew 30 to provide the degree of frictional resistance desired for opposing sliding movement of the carriage 26. A cable 32, affixed to one end of the carriage 26, passes over a pulley 34 supported by the frame 22 and is tensioned by a suitable weight 36 tending to draw the carriage 26 toward the roll 10. Another cable 38 (Fig. 1), affixed to the opposite end of the carriage 26, passes over pulleys 40 and 42 mounted in the frame 22 and is attached to a treadle 44 which is fulcrumed on a rod 46 mounted in suitable bearings in the frame 22.

A bracket 48 (not completely shown) secured to the frame 22 and having an opening for the cable 38 is engageable with a block 50 movably attached to the cable 38 for the purpose of adjustably limiting the extent of travel of the carriage 26 toward the roll 10 effected by the weight 36.

A second treadle 52, also fulcrumed on the rod 46, has secured to it one end of a cable 54. The other end of the cable 54 is connected by means of a pin 56 to the forked lower end of a last supporting jack 58 which is vertically slideable in a guideway 60 (Fig. 2) of the carriage 26. A pin 62 affixed to the carriage 26 projects into a slot 64 of the jack 58, and a spring 66 depending from the pin 62 is secured at its lower extremity to the jack 58. The spring 66 thus serves yieldingly to support the jack 58 in a heightwise position relatively to the carriage 26 and the roll 10. A stop screw 68 (Fig. 1) is threaded through a bracket 70 (not completely shown) secured to the frame 22 and engages treadle 52 for the purpose of adjustably limiting the height to which the jack 58 may be raised relatively to the roll 10 by the spring 66.

A substantially horizontal last pin 72 is secured in the upper portion of the jack 58 by a pin 74. For use with lasts of the two-part jointed type, a last-locking cam 76 is provided which is

mounted for pivotal movement about the last pin 72 (Figs. 1, 2 and 6). The cam 76 is in the form of a flat plate, its last-engaging perimeter being eccentric with respect to the axis of the last pin 72. Conveniently, this eccentricity of the cam 76 provides a last-engaging arcuate surface disposed to accommodate the distance from the thimble of any last on the last pin 72 to the face of its last cone, a dimension which may vary considerably in different styles and sizes of lasts. It will be understood that the cam member 76 is detachably mounted and may be dispensed with when working with solid or non-jointed lasts.

A rest 78 (Figs. 1, 2 and 7) for cushioning the cone tip of the last is secured to the jack 58 by a bolt 80 threaded to receive a wing nut 82 and washer 84. The rest 78 is in the form of a channel-shaped block disposed heightwise of the jack 58, the channel having inwardly inclined side-walls loosely engageable with the sides of the front cone of the last to aid in limiting its turning movement about a vertical axis, and a vertical bed 86 which may be covered with a suitable resilient material such as rubber to seat the last cone tip and provide the forepart of the last with lateral support against collapse. A projection 88 of the rest 78, through which the bolt 80 extends, has curved sides engaging an arcuate slot 90 in the jack 58 and permits the rest 78 to be moved, together with the last locking cam member 76 when used, so as to position and hold the last angularly about the last pin 72.

In operation, the treadle 44 will first be depressed to retract the jack 58 and carriage 26 from the operating range of the roll 10. A shoe unit S is then partially mounted by hand on the last L and, with the toe down, the last is placed on the last pin 72. Assuming that a two-part jointed last is being used and that the last is in its extended condition, it is locked in non-collapsible operating position with its cone tip against the bed 86 of the rest 78 by means of the cam 76 which is rotated about the last pin 72 by hand until the eccentric peripheral surface of the cam abuts the inner face of the cone tip as shown in Fig. 6. Any operating thrust tending to break the last is accordingly opposed by wedge-like support of the cam 76. For reasons explained below, the rest 78 and the last L may then be swung with the cam 76 about the last pin 72 so as to incline slightly from the vertical, and having determined the appropriate degree of this adjustment from previous experience with the style of last being utilized, the operator will then turn wing nut 82 to secure the last in adjusted position. As the roll 10 rotates relatively slowly into the initial position shown in Fig. 1, i. e., as it is about to begin its advance toward the last, the treadle 44 is released until block 50 engages bracket 48 thereby permitting the weight 36 to draw the carriage 26 and the jack 58 toward the roll 10 into a position wherein the roll, as it rotates, will come into frictional contact with the bottom of the forepart of the shoe unit S. The steady pressure exerted by the roll during this contact effects traction adequate for the initial movement of the forepart of the shoe unit upward relatively to the last. It will be understood that if different pressure is desired in operation on other shoe units the weight 36 may be suitably changed and the setscrew 30 adjusted as seems desirable.

As the roll 10 continues to rotate, it continuously exerts upon the surface bottom of the shoe unit an upwardly directed frictional force, the

locality of application of which progresses upwardly in the different successive positions of contact illustrated in Figs. 3, 4 and 5.

The carriage 26 yields horizontally along its guideway under the horizontal component of thrust of the rotating eccentric roll 10 against the shoe unit bottom, while the weight 36 holds the shoe unit bottom against the roll with a predetermined pressure. The upward traction of the roll 10 on the bottom surface of the shoe unit is roughly proportional to the resistance to lateral movement of the last as afforded by the weight 36 and the guideways acting on the carriage 26.

It will be noted that the eccentric motion of the roll 10 in itself is such as to transfer the locality of its frictional engagement upwardly lengthwise along the shoe unit bottom. The operator can lower jack 58 to extend the vertical range of such engagement, and he can increase the rate at which the locality of engagement may be transferred along the shoe unit bottom, by depressing the treadle 52. Also, if he so desires, he may assist in the operation by pressing downwardly by hand on the top of jack 58, thereby yieldingly lowering the jack 58 and the last L relatively to the shoe contacting zone of the roll 10, and causing the forepart of the shoe unit bottom to be wiped more rapidly upward over the corresponding portion of the last and transferring the frictional wiping over the ball line well into the shank portion. In this connection an operator may find it preferable to retard downward movement of the last when the shoe contacting portion of the roll 10 is at the ball line of the shoe unit bottom (Fig. 4), thus allowing frictional action of the roll to tension and distend the shoe unit over the forepart of the last. The shoe contacting portion of the roll 10 will then normally be farthest from the shaft 16. By further depression of the treadle 52 to further lower last L the upward wiping action of the roll 10 is transferred upwardly and inwardly over the shank portion of the shoe unit bottom, pressing the latter snugly over the corresponding portion of the last bottom, as shown in position 4, Fig. 5. At this stage of the operation the roll 10 may have started to reverse its horizontal component of movement, and the weight 36 will continue to maintain operative pressure between the surface of the shoe unit bottom and the roll 10. With the wiping of the shank portion of the shoe unit upwardly over the corresponding portion of the last, the working cycle of the roll 10 is completed. The treadle 52 is then released and the treadle 44 is depressed to move the jack 58 away from the operating range of the roll 10 to where the back portion of the shoe may be manually drawn over the back of the last and the lasted unit may be removed from the machine.

As has been noted above, the last L may have been angularly turned with the cam 76 and the rest 78 about the last pin 12 so as to incline from the vertical. Slanting the last relatively to the roll 10 in this manner adjusts the area of contact transversely between the roll and the bottom forepart of the shoe unit and provides an accommodation for the swing of the last which is important in securing appropriate distribution of traction for the even relasting of the entire shoe forepart. The optimum degree of slant to be given successive lasts is readily determined and normally constant for shoes of the same or similar style. The angular setting of the rest 78 may be easily modified when the last styles are changed. Moreover, with more diffi-

cult shoes to be relasted an operator may vary the inclination of each last manually during operation of the roll so as to attain traction along each shoe bottom in the several directions desired. Because of the transverse pitch of the last bottom, such directional changes in the draw of the roll may readily be made to assure alignment of a seam in the upper with the bottom edge of the last.

What is claimed as new and desired to be secured by Letters Patent of the United States is:

1. In a machine for effecting relative movement between shoe units and lasts, a support for a last, and a friction tool engageable with a shoe unit on the last to move the shoe unit relatively to the last, said tool comprising a driven eccentric roll.

2. A machine for mounting shoe units on lasts comprising a driven eccentric roll, and a support for a last constructed and arranged to enable the forepart of the bottom of a shoe unit on the last yieldingly to engage said roll, the eccentricity of the roll serving to shift the locality of its engagement with the shoe unit bottom from the forepart to the shank portion, and the roll operating frictionally to urge the shoe unit rearwardly on the last wherever it engages the shoe unit bottom.

3. A machine for mounting shoe units on lasts comprising a driven eccentric roll frictionally engageable with a shoe unit bottom, a support for a last having the shoe unit partially mounted thereon, means for moving the support yieldingly to hold the last in operating position relatively to the roll, and means for varying lengthwise along the shoe unit bottom the locality of engagement of the shoe unit bottom with said roll, the last-mentioned means serving to extend the operating range of said roll along the shoe unit bottom.

4. In a machine for mounting shoe units on lasts, a driven eccentric roll frictionally engageable with the bottom of a shoe unit partially mounted on a last, a jack for supporting the last, a carriage for supporting said jack, a guideway along which the carriage is horizontally movable to move the last and the shoe unit thereon toward and from the roll, said jack being mounted for heightwise movement in said carriage, means for urging said carriage along said guideway to hold the shoe unit bottom pressed against the roll, and means for moving the jack heightwise in the carriage to shift the locality of operation of the roll upon the shoe unit bottom.

5. A machine for mounting shoe units on lasts comprising a driven eccentric roll frictionally engageable with the bottom of a shoe unit partially mounted on a last, a jack carrying a last pin engageable with the back cone of the last and a rest engageable with the front cone of the last, a support for the jack, means acting upon said support to hold the shoe unit bottom pressed against the roll, said jack being movable in said support to shift the locality of engagement of the roll upon the shoe unit bottom, means for so moving the jack in the support, and means for adjusting the inclination of the last relatively to the roll to change the direction of frictional engagement of the latter on the shoe unit bottom whereby relative movement between the shoe unit and the last may be effected to accommodate the degree of swing of the forepart of the last.

6. A machine for mounting shoe units on lasts

comprising a driven eccentric roll frictionally engageable with the bottom of a shoe unit partially mounted on a collapsible last, a jack for supporting the last, a carriage in which the jack is mounted, said carriage being movable horizontally to move the shoe unit bottom toward and from the roll, means acting on the carriage to hold the shoe unit bottom in operative contact with the roll, a last pin secured to said jack and engageable with the back cone of the last, a rest associated with said jack for receiving the front last cone to sustain the latter against the operating thrust of the roll and also to hold the last in a predetermined angular position about the last pin, means for adjusting the rest angularly with respect to the last pin to vary the angular position of the last, and a cam mounted for turning movement about said last pin arranged to engage the front cone of the last, said cam serving to lock the forepart of the last against collapse during operation of the roll on said shoe unit bottom.

7. In a machine for mounting shoe units on lasts, a driven roll mounted eccentrically, a carriage movable horizontally with respect to said roll, a jack mounted in said carriage yieldable heightwise of said roll for supporting a collapsible last having a shoe unit partially mounted thereon, means acting upon said carriage to hold the bottom of the shoe unit in frictional contact with the roll, means engageable with the last for setting the angle with which the shoe unit bottom engages the roll, and means for locking the last in extended condition to prevent its collapse during the wiping action of the roll over the shoe unit bottom.

8. A machine for mounting shoe units on lasts comprising a driven friction roll mounted for eccentric rotation about a fixed axis, a support for a last on which a shoe unit is partially

5 mounted, means for yieldably urging the support toward the friction roll to hold the shoe unit bottom against the roll, a front last cone rest, means for setting the rest angularly with respect to the roll to maintain the last and shoe unit in a desired angular position, and treadle controlled means for effecting relative movement between the eccentric roll and the last support to extend the range of operation of the eccentric roll along 10 the bottom of the shoe unit to move the shoe unit further onto the last.

9. A machine for mounting shoe units on lasts comprising a driven eccentric roll frictionally engageable with the bottom of a shoe unit, a support for a last on which the shoe unit has been partially mounted, a carriage for said last support, means acting on said carriage to maintain the last in yieldable operative position relatively to the roll, means associated with said carriage for shifting the locality of engagement 15 of said roll along the shoe unit bottom, and adjustable means on said support for holding the last rigidly during such engagement in selected angular relation to said roll.

10. In a machine for effecting relative movement between a collapsible last and a shoe unit thereon, a friction tool engageable with the bottom of the shoe unit, a last pin engageable with a thimble hole in the rear cone of the last, and a pivotally mounted cam having an eccentric periphery which is engageable with the front cone of the last to hold the last distended, rotation of the cam serving to bring its periphery into operative engagement with the front cone 35 of the last regardless of the dimensions of the last.

CHARLES E. JOHNSON.
